UNITED STATES PATENT OFFICE.

NORBERT M. LA PORTE, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

PACKAGING-MACHINE.

1,169,499.

Specification of Letters Patent. Patented Jan. 25, 1916.

Application filed August 6, 1910. Serial No. 575,922.

To all whom it may concern:

Be it known that I, NORBERT M. LA PORTE, a citizen of the United States, residing at Baltimore, State of Maryland, have invented certain new and useful Improvements in Packaging-Machines, fully described and represented in the following specification and the accompanying drawings, forming a part of the same.

This invention relates to improvements in packaging machines, and more particularly to machines for packaging liquids, although, as to some of its features, the invention may be embodied in machines for packaging substances other than liquids.

The invention has for one of its objects to produce an improved packaging machine constructed to fill, and, if desired, also to close, a plurality of containers, the construction being such that the containers are fed to the filling, and to the closing mechanism, if desired, in rows arranged across the line of feed.

A further object of the invention is to produce a packaging machine adapted to fill a plurality of containers fed thereto in rows extending crosswise of the line of feed, and, if desired, to close the same, the construction being adapted to present rows of containers in separated groups, whereby the machine may be effectively employed in connection with containers arranged in receptacles, such, for instance, as shipping cases, each case with its containers being placed in and automatically operated upon by the machine.

A further object of the invention is to produce a packaging machine of such a character that the containers may have the level of the material therein automatically determined.

A further object of the invention is to produce a packaging machine more especially adapted to the packaging of liquids which are liable to foam during packaging because of trapped air or gas, the machine being so constructed as to permit the subsidence of the foam before the packaging is completed.

The invention also extends to certain details of construction not necessary to particularly specify which will be hereinafter fully pointed out.

With these and other objects not specifically referred to in view, the invention con-

sists in certain constructions, and in certain parts, improvements and combinations as will be hereinafter fully described and then specifically pointed out.

Referring to the accompanying drawings, which illustrate one embodiment of the invention,—Figure 1 illustrates in side elevation, partly in section, a machine constructed in accordance with the invention. Fig. 2 is a front elevation of the construction illustrated in Fig. 1. Fig. 3 is a section on the line 3—3 of Fig. 1. Fig. 4 is a plan view, certain parts being broken away, of the machine illustrated in Fig. 1, showing the feed mechanism employed in the machine illustrated in Fig. 1. Fig. 5 is a section on the line 5—5 of Fig. 1, illustrating more particularly the construction of the feed mechanism, the filling and capping mechanisms being broken away. Fig. 6 is a detail sectional view, on the line 6—6 of Fig. 4, illustrating the construction of the endless conveyer employed in the machine shown in Fig. 1. Fig. 7 is a sectional diagrammatic view illustrating more particularly the operation of the filling and level determining mechanism, the parts being shown in inoperative position. Fig. 8 is a diagrammatic sectional view generally similar to Fig. 7, illustrating the operation of the filling mechanism, the parts being shown in operative position. Fig. 9 is a diagrammatic sectional view illustrating the operation of the level determining mechanism. Fig. 10 is a sectional view of one of the capping devices of the machine shown in Fig. 1. Fig. 11 is a detail view of a pawl and ratchet feed which may be employed. Fig. 12 is a detail view of a brake mechanism which may be employed in connection with the feed mechanism.

Machines embodying the invention will usually include a feeding mechanism constructed to advance the containers to be filled, the containers being arranged in rows across the line of feed, and, in the best constructions embodying the invention, the containers will be advanced in separate groups.

While the construction of the feeding mechanism may be varied widely, in the particular construction illustrated, two drums or cylinders 2, 3 are provided, the drum 2 being mounted on a shaft 4 suitably supported in the side frames 1, and the

drum 3 on a shaft 5. In the construction illustrated, this shaft 5 is mounted in sliding boxes 6, these boxes being held in their adjusted position by means of set-screws 7, as usual in such constructions. The drums referred to, when the character of feeding mechanism illustrated is employed, operate to support a carrier which may be conveniently formed of separated steel belts 8 working in grooves 9 in the drums.

As has been indicated, in the best constructions the feeding mechanism will be of such a character as to advance the containers in separated groups. While the construction by which this is effected may be varied, in the machine illustrated, the steel belts 8 are provided with a series of platforms 10 spaced from each other. While the construction may be varied in this respect, in the particular construction illustrated, the platforms 10 are made up of a series of blocks 11 provided with grooves which enable them to be slid into U-shaped cross-pieces 12 connected by rivets 13 to the belts 8, the grooves 9 affording space for the rivet heads to pass around the carrier. By making the platform of separate blocks in the manner shown, they flex readily as they pass around the drums, thereby conducing to the easy operation of the carrier.

The machine illustrated is particularly designed for the packaging of liquids, such, for instance, as milk. Milk, as is well-known, is usually packaged in bottles, the bottles being shipped in cases. A form of case quite generally employed is that illustrated in the drawings (see Fig. 5) in which the sides are formed of wooden boards 14 and the bottom is formed by wires 15, a separate receptacle for each bottle being obtained by the use of intersecting wires 16. The machine illustrated is particularly adapted for the packaging of milk bottles, indicated at 17, while the bottles are in place in such cases. It will be observed that the cases referred to have apertured bottoms and are slightly deeper than the vertical height of the bottles. When the machine is to be employed in connection with cases having apertured bottoms, the platforms will, in the best constructions, be so constructed as to afford a firm support for the bottles during the operations to which they are subjected in the machine, and when the cases are, like those illustrated, slightly deeper than the height of the bottles, the construction provided will be such as to raise the bottles above the top of the cases.

While the platforms may be variously constructed to effect the results referred to, in the particular construction shown, each platform is slightly less in area than the interior of the case and the blocks which compose it are provided with grooves 18 which receive the bottom wires, so that when

the case containing the bottles is placed upon the platform, the bottom wires will be received in the grooves and the bottles firmly supported by the blocks.

While the platforms referred to may be variously arranged on the carrier, when this form of feeding mechanism is employed, in the best constructions the platforms will be spaced, as indicated at 19 (see Fig. 6) and the length of these spaces will bear a certain definite relation to the relation of the mechanisms to the operation of which the containers are to be subjected.

The mechanism for operating the endless carrier, when this type of feeding mechanism is employed, may be varied within wide limits. In the particular construction shown the shaft 4 of the drum 2 is provided at each end with ratchet wheels (see Figs. 1, 2 and 11) having a series of teeth 20 having overhanging ends 21, and other teeth, as 22, one of these teeth 22 being located between each series of the teeth 20. The teeth referred to are engaged by a pawl 23 pivoted on pawl carrying arms 24 loosely mounted on the shaft 4. These pawl carrying arms are operated by a turnbuckle connection 25 from levers 26 mounted on a shaft supported from the machine frame. The levers 26 are provided with cam rolls 27 engaging grooves 28 in closed cams mounted on a shaft 29. The shaft 29 is provided with a gear 30 in mesh with a pinion 31 mounted on a shaft 32 which is the main driving shaft of the machine.

It will be observed that, with the construction described, the pawl-carrying arms 24 have a constant throw, but that they impart variable movements of arc to the ratchet wheel. The teeth 22 are equal in length on the root-circle to two of the teeth 20. When, however, the pawl is operating on the teeth 20, while its stroke is equal to two of the teeth, it is kept from dropping in behind the second tooth by the overhang 21, so that the pawl has a lost motion when operating on the teeth 20 equal to the length of one tooth. The teeth 22, however, have no such overhang, and, therefore, the pawl, when operating on these teeth, gives the ratchet wheel a movement of arc equal to twice the movement of arc which it receives when the pawl is operating in connection with the teeth 20. The reason for this construction will be adverted to hereafter.

In the best constructions embodying the invention, and particularly where feeding mechanism of the type illustrated is employed, the mechanism will include suitable brake mechanism to prevent overthrow of the feed. While the brake mechanism employed may be of any suitable type, in the construction shown there are employed two brake shoes 33 which operate on the periphery of the drum 2 (see Figs. 1, 5 and 12) 130

these brake shoes being pivoted on studs 34, the shoes being backed up by springs 35, as is usual in such constructions. The studs 34 are mounted in hubs 36 on arms 37 fast on a shaft 38, this shaft being the shaft on which the lever 26 before referred to is mounted. With the construction described, as the lever 26 completes its forward movement, it rocks the shaft 38 and throws the brake shoes into braking contact with the drum 2.

It has been heretofore stated that the platforms on which the cases are supported are slightly less in area than the interior of the cases. To provide for variations in cases due to variations in original construction or to warping or other causes, each platform may be provided (see Figs. 4 and 6) with a hook plate 39 which engages the forward side of the case when the same is in position on the platform. This construction not only provides for the variations referred to but also enables the travel of the endless belt to be slightly shortened, because the length of the platform may be made sufficiently less than the length of the case to permit the platform to bend and the blocks composing it to open somewhat before the case is removed from the platform.

30 Machines embodying the invention in its entirety will include a chamber in which the material to be packaged is contained. While the construction and location of this chamber may be varied, in the particular construction illustrated it consists of a metal receptacle 40 supported on standards 41 secured to the side frames of the machine. In the construction shown, this chamber is provided with an inlet pipe 42 controlled by a valve 42^a. In the best constructions embodying the invention this valve 42^a will be a three-way valve and will also control a steam pipe 42^b (see Fig. 3). The chamber may also have a draw-off pipe 43 similarly valved, to enable any surplus to be withdrawn from the chamber.

The filling mechanism employed in machines for carrying the invention into effect may be widely varied. It has been found in practice that in filling containers with certain kinds of material the filling of the first part of the container can be accomplished much more rapidly than the last part of the container. Thus, in filling containers with a liquid, and particularly with a liquid which tends to foam, it has been found that the time required to introduce the last quarter of the contents is about equal to the time required for introducing the first three quarters. In machines embodying the invention in its best form, therefore, the means for supplying the material to be packaged should include a primary filling mechanism by which a considerable proportion of the contents is introduced into the container

and a secondary filling mechanism for introducing the remainder of the contents, the containers or receptacles being successively presented to these mechanisms. This enables the mechanism to operate rapidly, as 70 the secondary filling of one receptacle can be proceeded with as the primary filling of the next receptacle is taking place. Where, as in the particular machine illustrated, a plurality of containers is to be simultaneously filled, the chamber which contains the material to be packaged, and which may be closed by a cover, as 44, may advantageously have in connection therewith a row of filling tubes which may constitute the 80 primary filling mechanism. The construction of the tubes employed in the machine illustrated is well shown in Figs. 7 and 8.

As shown, each filling tube 45 passes through a stuffing box 46, and has at its 85 lower end a nipple 47 adapted to enter the mouth of the container to be filled. In the best constructions embodying the invention the filling tubes will be mounted to receive vertical movements of variable lengths, so 90 that they may be effective with containers of varying heights, and each tube will also be provided with means for effecting a seal between the tube and the mouth of the container.

95 While the construction by which the tube is given the movements referred to and by which the seal is effected, may be varied, in the particular construction illustrated, each filling tube is provided with a shoulder 48 100 on the under side of which is located a sealing gasket 49. Resting upon this shoulder is a spring 50 which bears against a collar 51 formed on a tube 52 which is a part of the stuffing box construction. This tube 52 is 105 threaded into the coöperating part of the stuffing box, as is usual, and the construction is such that the spring 50 is under an original compression. A suitable valve will be 110 provided for each filling tube. While the construction and arrangement of these valves may be varied, in the particular construction illustrated, each valve, marked 53, is provided with a venting chamber 54 having perforations 55 through its walls. This 115 chamber communicates with a hollow stem 56 by which the valve is operated. In the best constructions embodying the invention, and as shown, the valve operating means will be of such a character that the movement of the filling tube produced by the spring is controlled or at least permitted by the valve and its operating means, and the movement of the filling tube in opposition to the spring is produced by the valve 120 and its operating means. In the particular construction illustrated, each of the valve stems 56 passes loosely through and is connected by nuts 57 with cross bars 58 in turn connected to side bars 59, the parts forming 125

an operating frame. In the particular construction illustrated, this operating frame is given a vertical reciprocating movement. While the means by which this is accomplished may be varied, as shown, the side bars 59 have connected thereto operating rods 60 which work through tubes 61 screwed into or otherwise secured to the bottom of the chamber 40. These operating rods are, in the particular construction illustrated secured to a bar 62 connected to a vertically movable rod 63, a brace 64 being employed, if desired, to stiffen the construction. There may be one of these rods 63 on each side of the machine and they may work through guides 65, 66 secured to the machine frame. In the particular construction illustrated, furthermore, these operating rods 63 are operated from the cams containing the grooves 28, there being one of these cams on each side of the machine. As shown, the rods 63 are provided with cam rolls 67 which work in the cam grooves 28. The valves 53, in the particular construction shown, work 25 against the mouths of the nipples 47.

In the construction as described, it will be understood,—and assuming that bottles or other containers are in position to be filled beneath the filling tubes,—as the frame 30 is moved down (it being remembered that the springs 50 are under an original compression) the filling tubes will follow the valves, which move down by gravity, until the sealing disks 49 strike the mouths of the 35 containers and effect a seal thereagainst. A further downward movement of the frame permits the valves to move away from the nipples 47 and the material in the tank is allowed to flow out of the tubes into the 40 containers, the action of the parts, in the particular machine illustrated, being well shown in Fig. 8.

While the venting construction may be varied, that shown is particularly advantageous, because it has been found in practice that when filling a container like a bottle the air therein tends to be forced upward in a column which is substantially central to the container. The construction shown 50 enables the air to readily escape without being compelled to cross the circular stream of the entering liquid.

It will be noted that the valves 53 are approximately cone-shaped, that is to say, the upper portion which forms the seal against the mouth of the nipple 47 has a general cone-shape in outline, and the part below the venting chamber has also a general conical form. This construction is particularly advantageous in filling a narrow mouth container such as a bottle. The lower cone-shaped part of the valve will act, in case a container is slightly out of center, to position the same, and the upper cone-shaped part will act as a spreader to

throw the liquid out against the sides of the container.

The character of the secondary filling mechanism employed, when the supplying mechanism includes both primary and secondary filling mechanisms, may be varied within wide limits. It is desirable, in some packaging machines that the level of the material in each container be accurately determined. Machines, therefore, which embody the invention in what is regarded as its best form will include means for thus accurately determining the level of the material in each container, and the secondary filling mechanism may well be constructed so that in addition to completing the filling of the container, it will also effect this level determining function. While the particular construction of the devices by which this is accomplished may be varied, in the particular construction shown, the secondary filling mechanism includes tubes 68. When, as in the machine illustrated, a plurality of primary filling devices are employed, a plurality of secondary filling devices similarly arranged should be employed.

In the particular machine illustrated, the primary filling mechanism comprises a set of three filling devices adapted to fill three containers. The secondary filling mechanism, therefore, also includes three filling devices, but for reasons which will hereinafter appear, the particular secondary filling mechanism illustrated also includes two additional sets of filling devices. As these secondary filling devices are duplicates, only one need be described. In each of them the tube 68 passes through a stuffing box 69 and is provided near its lower end with a shoulder 70 on which is secured a sealing disk 71. A nipple 72 is screwed into the disk 70. A sleeve 73 is provided, this sleeve forming a part of the stuffing box construction, the sleeve being provided with a collar 74. A spring 75 is located between the disks 70 and the shoulders 74, this spring being maintained under original compression. The mouth of the nipple 72 is closed by a valve 76 corresponding generally in outline to the valve 53 before referred to, and having in general the same function. The valve 76 is provided with an operating rod 77 connected by nuts 78 with the operating frame comprising the bars 58, 59.

In the operation of the particular machine illustrated, the containers of a row after having received from the primary filling mechanism a considerable proportion of their contents, pass to the secondary filling mechanism and are presented to the tubes 68 of that mechanism. As the operating frame descends, the tubes 68 are moved downward by their springs 75 and if a container is properly located beneath one of these tubes, the nipple 72 enters the mouth 130

of the container and the disk 71 which surrounds the nipple forms an hermetic seal with the mouth of the container, the action being substantially the same as that described in connection with the primary filling devices. A further downward movement of the frame permits the valve 76 to move away from the mouth of the nipple 72. The operation which takes place following the opening of the mouth of the nipple by the movement of the valve will depend upon the condition of the container into which the nipple has been inserted. Referring to the second row of containers, that is, the row next the row which is under the primary filling tubes, if the primary filling mechanism has operated properly, this row of containers will be about three-quarters full. In that case, as the mouth 72 of the tube 68 is opened, the material will flow into the container and will rise therein until it reaches the mouth of the nipple at which point the trapped air in the space between the nipple and the mouth of the container will, if a hermetic joint has been formed between the mouth of the container and the gasket 71, prevent any further discharge into the container. As the amount of the contents of the container displaced by the valve 76 can be readily determined, when this valve rises and closes the mouth of the nipple 72, and the nipple and tube 68 are withdrawn from the container, the contents should be at the level desired. If, for any reason, however, the primary filling tubes have not acted properly, as, for instance, if because of a chip in the lip of a container a tight joint has not been established between a gasket 49 and the mouth of a container, the container may be overfilled. When such an overfilled container passes to the secondary filling mechanism, as the nipple 72 and the valve 76 descend into the container they will displace the excess of liquid therein which excess will run over the mouth of the receptacle. If a tight joint be established by the gasket 71 with the mouth of such container, as the valve 76 opens no liquid will flow from the tube 68 into said container, but the valve will open and close idly. In either case, whether material is introduced into the containers by the secondary filling tubes or displaced therefrom by the tubes, the level will be determined by these tubes.

It will be understood that both the springs 50 and 75 are under such compression that in case no container is under the filling and regulating devices, the tubes 45 and 68 will follow the downward movement of the valves, so that the valves will not be opened. There is, therefore, no loss of fluid in case the containers fail to be presented to either the filling or regulating devices.

It will be noted that in the machine shown the group of filling devices are located at

a considerable distance from the group of level determining devices. This is also important in filling containers, such as bottles, with liquids which foam because of trapped air or gas. In handling such liquids, if the 70 contents are exposed to the air, the foam subsides with comparative rapidity. In the particular machine shown, the space between the filling tubes 45 and the first set of regulating tubes 68 is so calculated that 75 the containers in passing from the filling devices to the regulating devices will be exposed to the air a sufficient length of time to allow the foam to subside.

It has been pointed out that, in the particular machine shown, there are three cross-wise rows of the regulating devices. This machine is designed to fill milk bottles arranged in cases, each case containing twelve bottles arranged in four rows, each row having three bottles, the cases being placed successively in the machine. The feeding mechanism is so designed that the stroke of the pawl, when coöperating with a long tooth 22, will bring the first row of bottles in each 90 case beneath the filling devices. The case is now advanced by a step by step movement equal to the distance between the bottles in the case by the pawl 23 coöperating with the teeth 20, after which the pawl again coöperates with another of the teeth 22 and advances the case, so that the first row of bottles in the case is brought beneath the first set of regulating devices which complete the filling and determine the level. 100

It may happen, especially if the machine is running rapidly, that the level will not be accurately determined by the first set of regulating devices. Therefore, to insure absolute accuracy, the second and third set of 105 regulating devices, which, as has been pointed out, are duplicates of the first set, are provided. As the feed continues the first two rows of bottles in the case will be successively presented to all three of the 110 sets of regulating devices. While, however, the second row of regulating devices may, as pointed out, have some effect in determining the level of the contents of the bottles which are presented to it, as a rule, 115 the third row will open and close without in any way affecting the level of the liquid in the bottles. After the first two rows of bottles have been presented to the regulating devices, the parts are in the position 120 shown in Fig. 1, at which time the first two rows of bottles have been entered by the nipples of all the regulating devices. The parts are now in the position, however, when the long movement of the feeding mechanism takes place. This causes the case to be advanced to a position where the last row of containers in the case is brought under the last row of regulating devices. In other words, in the operation of the feed, the first 130

two rows of bottles will be presented to all the rows of regulating devices, although the last row, as a rule, has no effect on the level of the liquid in these bottles, the next, or 5 third row of bottles, will be presented to the first and second rows of regulating devices, and the fourth row of bottles to the first and third rows of regulating devices. This construction insures that all the bottles in 10 each case will be presented to at least two of the regulating devices.

In machines embodying the invention in its best form, the containers, after being filled, will be sealed or stoppered while still 15 in the machine. In machines which embody the invention in its best form, the closing mechanism will not only operate to close a container or containers while another container or containers is being operated upon 20 by the filling mechanism, but the means by which the filling and closing operations are effected will be common to both mechanisms. The containers, however, which are operated upon may vary in height or capacity, and as the stroke of the operating means, whatever be its construction, should be such as to bring the filling and closing mechanisms into operation, either these mechanisms or the operating means should be such 25 as to effect the results desired irrespective of variations in the containers. For instance, containers such as bottles intended to be of the same size will vary somewhat in height, and containers holding different 30 amounts may vary considerably in height. The construction should be such, therefore, that the filling and closing will be effected notwithstanding these variations.

When the containers are to be closed in 40 the machine, the closing mechanism may be of any desired type. The means for presenting the containers to said closing means may also be of any suitable type. In the particular machine illustrated, however, the 45 means for presenting the containers to the closing mechanism and supporting them is the feeding mechanism which has been heretofore described, the variable movement of the mechanism being utilized to properly 50 present the containers in the cases to the closing means. In the particular machine shown, the closing is effected by applying to the containers the well-known type of crown cork indicated at 80 (see Fig. 10). 55 While the construction may be varied in this respect, these crown corks are applied by means of movable capping heads 81 which are intermittently reciprocated toward and away from the containers. As 60 shown, these capping heads are mounted on a cross-head 82 moving in guides 83 secured to the front of the chamber 40. When reciprocating stoppering devices are employed, the actuation thereof may be effected in any

desired way. In the particular construction 65 illustrated, however, the rods 63 are secured in any suitable way, as by nuts 84, to eyes 85 cast on the cross head 82. This insures that the movement of the capping dies occurs in synchronism with that of the filling and 70 level determining mechanisms.

If desired the crowns may be automatically fed to the capping heads. In order to effect this, in the construction shown, the cross-head 82 is provided with a bracket 86 75 which supports a crown feeding and selecting hopper 87 of a construction well-known in the art. This hopper communicates by means of a channel 88 and branches 89 with the several heads referred to. In order to 80 balance the movements of the various mechanisms operated by the rod 63, a counter-weight 90 may be employed mounted on levers 91 resting on a bar 92 mounted in the frame and connected to the rod 63. 85

The particular construction of the capping mechanism may, as has been indicated, be considerably varied. It is desirable, however, that this mechanism be of such a character as to take care of, without breaking, 90 bottles of varying heights, and to effect this, means should be provided for effecting the capping with a yielding pressure. While this may be accomplished in various ways, in the construction shown, each of the heads 95 81 is provided with a bending die 93 seated on a throat ring 94, this ring being held in position by a beveled guide nut 95 secured to the lower end of the capping head, the beveled opening in this nut facilitating the 100 entrance of the bottle heads thereinto. The throat ring is shouldered, as indicated at 96, to support the crowns, the crowns being delivered to these rings by the branch chutes 89 before referred to. As shown, the bending dies are yieldingly held against the pressure developed during the crowning operation. While the means for thus yieldingly holding the bending dies in place may be varied, as shown, this is effected by a spring 105 96 resting against a washer 97 above the bending die and against a threaded washer 98 screwed into the upper end of the capping head threaded to receive it. This spring is normally under an original compression 110 which is sufficient to effect the inward bending of the flange of the crowns for the shortest bottles which may be presented thereto, and, at the same time, the character of the spring is such that the longest bottles 115 presented thereto will not place it under sufficient tension to break the bottles. By this construction not only can bottles of varying heights which are presented to the same bending die be capped, but the mechanism will effectively cap containers of 120 varying heights in the same crosswise row which is particularly important where the 125

machines are, as in the machine illustrated, designed to cap a plurality of bottles arranged in such rows.

The caps are held in position prior to the bending operation by a plunger 99 having a head 100 thereon, this plunger being slotted, as indicated at 101, the slot engaging a cross-pin 102 to limit the downward movement of the plunger, and the plunger being backed up by a light spring 103. The dies are also provided with a headed plunger 104 backed up by a spring 105, the upper end of this plunger working in an opening 106 in a guide nut 107 which closes the upper end

15 of the head. The function of this plunger is to insure that the capped bottles be delivered after capping from the bending dies.

The operation of the mechanism will be understood from the foregoing description.

20 It will be seen that the machine is capacitated to fill, accurately determine the level, and cap bottles or other similar containers, and that this can be carried on continuously and rapidly.

25 The construction is also such that the apparatus can be rapidly and effectively cleaned, which is of particular importance where liquids such as milk are to be packaged. By turning the three-way cock 42^a so 30 as to connect with the steam pipe 42^b the chamber may be filled with steam which may be allowed to escape through the filling tubes and the level determining tubes, so that all the parts of the mechanism with 35 which the milk comes in contact can be thoroughly scalded out.

Changes and variations may be made in the construction by which the invention claimed is carried into effect. The claimed 40 invention, therefore, is not to be limited to the particular construction hereinbefore described and illustrated in the accompanying drawings.

What is claimed is;—

45 1. A machine for packaging liquids, including, in combination, a primary filling apparatus arranged to deliver to a container a primary filling charge, a secondary filling mechanism arranged to remove a part of 50 the primary charge or to supply a supplemental charge thereto, whereby each container is finally charged to a predetermined level, and means for advancing containers while open, from the primary filling mechanism to the secondary filling mechanism.

55 2. A packaging machine including in combination a filling mechanism, an endless carrier provided with a plurality of positioning platforms each adapted to support a 60 case holding a plurality of containers, each platform being less in size than the interior of the case placed thereon and being made up of a plurality of flexibly connected blocks, and means for giving the carrier a step-by-

65 step advancing movement to present the containers in the cases to the filling mechanism.

3. A packaging machine including in combination a filling mechanism, an endless carrier provided with a plurality of positioning platforms each adapted to support a 70 case holding a plurality of containers, each platform being less in size than the interior of the case placed thereon and being made up of a plurality of flexibly connected grooved blocks, and means for giving the 75 carrier a step-by-step advancing movement to present the containers in the cases to the filling mechanism.

4. A packaging machine including in combination a filling mechanism, an endless carrier provided with a plurality of positioning platforms each adapted to support a case holding a plurality of containers, each platform being less in size than the interior of the case and being made up of a plurality 80 of flexibly connected removable blocks, and means for giving the carrier a step-by-step advancing movement to present the containers in the cases to the filling mechanism.

90 5. A packaging machine including in combination an endless carrier provided with a plurality of positioning platforms each adapted to support a case holding a plurality of containers, each platform being less in 95 size than the interior of the case and consisting of a plurality of flexibly connected blocks, means for giving the carrier a step-by-step variable advancing movement to compensate for the spaces between the cases, 100 and a filling mechanism comprising a row of filling devices arranged crosswise of the line of movement of the carrier.

6. A packaging machine including in combination a feeding mechanism comprising a 105 plurality of traveling platforms, each platform being made up of a plurality of flexibly connected blocks and being adapted to support a case holding a plurality of containers arranged in rows and being less in 110 size than the interior of the case, a row of filling devices extending crosswise of the line of feed, a row of stoppering devices extending crosswise of the line of feed, and means for operating the platforms to successively present the containers to the filling and stoppering devices.

115 7. A packaging machine including in combination a feeding mechanism comprising a 120 plurality of traveling platforms spaced apart, each platform being made up of a plurality of flexibly connected blocks and being adapted to support a case holding a plurality of containers arranged in rows and being less in size than the interior of the 125 case, a row of filling devices extending crosswise of the line of feed, a row of stoppering devices extending crosswise of the line of

- feed, and means for giving the platforms a variable step-by-step advancing movement to successively present the containers to the filling and stoppering devices and to compensate for the spaces between cases.
8. A liquid packaging machine including in combination means for introducing liquid into a liquid container, regulating means for determining the level to which the liquid rises in the container, and means for successively presenting the container to the introducing and regulating means.
9. A liquid packaging machine including in combination means for partly filling a container, means for completing the filling and determining the level to which the contents may rise therein, and operating devices for said means.
10. A liquid packaging machine including in combination means for partly filling a container, means for completing the filling of said container and determining the level to which the contents may rise therein, operating devices therefor, and means for successively presenting the container to said means.
11. A liquid packaging machine including in combination a source of liquid supply, a filling tube, a valve, a regulating tube for determining the level of the liquid in the container connected with the source of supply and having an orifice below the mouth of the container, means for forming an hermetic seal between the regulating tube and the mouth of the container, a valve for closing the orifice in the regulating tube, and means operating the valves, said operating means being timed to cause the container to be partly filled by the filling tube, the filling being completed and the level determined by the regulating tube.
12. A liquid packaging machine including in combination a source of liquid supply, a filling tube, a valve, a regulating tube for determining the level of the liquid in the container connected with the source of supply and having an orifice below the mouth of the container, means for forming an hermetic seal between the regulating tube and the mouth of the container, a valve for closing the orifice in the regulating tube, means for operating the valves, said operating means being timed to cause the container to be partly filled by the first tube, the filling being completed and the level determined by the regulating tube, and means for successively presenting the container to said tubes.
13. A liquid packaging machine including in combination means for introducing liquid into a container, a regulating mechanism for determining the level of the liquid in the container, said mechanism including a source of liquid supply, a tube connected therewith and arranged to enter the mouth of the container, said tube having an orifice which is below the mouth of the container when the tube is in operative position and affording the sole ingress and egress passage to and from the container, a valve for opening and closing said orifice, and means for forming an hermetic seal between the tube and the container mouth.
14. A liquid packaging machine including in combination means for introducing liquid into a container, a regulating mechanism for determining the level of the liquid in the container, said mechanism including a source of liquid supply, a tube connected therewith and arranged to enter the mouth of the container, said tube having an orifice which is below the mouth of the container when the tube is in operative position and affording the sole ingress and egress passage to and from the container, a valve for opening and closing said orifice, and means for forming an hermetic seal between the tube and the container mouth.
15. A liquid packaging machine including in combination a source of liquid supply, a filling tube in connection therewith, a valve for opening and closing the tube, a regulating tube also in communication with the source of liquid supply and arranged to extend into the mouth of the container, said tube having an orifice which is below the mouth of the container when the tube is in operative position and affording the sole ingress and egress passage to and from the container, a valve for opening and closing said orifice, means for forming an hermetic seal between the regulating tube and the container mouth, and means for operating the valves, said means being timed so that the supply from the filling tube is cut off before the container is filled.
16. A liquid packaging machine including in combination a source of liquid supply, a filling tube in connection therewith, a valve for opening and closing the tube, a regulating tube also in communication with the source of liquid supply and arranged to extend into the mouth of the container, said tube having an orifice which is below the mouth of the container when the tube is in operative position and affording the sole ingress and egress passage to and from the container, a valve for opening and closing said orifice, means for forming an hermetic seal between the regulating tube and the bottle mouth, means for operating the valves, said means being timed so that the supply from the filling tube is cut off before the container is filled, and means for successively presenting a container to the filling and regulating tubes.
17. A liquid packaging machine including in combination a source of liquid sup-

- 5 the source of liquid supply and being arranged to extend into the mouth of the container and having an orifice which is below the mouth of the container when the tube is in operative position, said orifice 10 affording the sole ingress and egress passage to and from the container, a valve for controlling said orifice, means for forming an hermetic seal between the regulating tube and the container mouth, means for operating the valves, said means being timed so that the supply from the filling tube is cut off before the container is filled, and means for successively presenting the container to said filling and regulating tubes.
- 15 18. A liquid packaging machine including in combination means for forwarding the containers in spaced groups, a filling mechanism, a plurality of regulating devices for determining the level of the liquid in the 20 containers, said devices being arranged to operate successively on the containers of a group, and means for operating the forwarding devices to present all the containers of each group to the filling mechanism and a part 25 of the containers of each group to some of the regulating devices and the remainder of the containers of each group to all the regulating devices, a stoppering mechanism to which the forwarding means presents the containers, and means for simultaneously 30 operating the filling mechanism, the regulating devices and stoppering mechanism.
- 20 19. A liquid packaging machine including in combination means for forwarding the containers in spaced groups, a filling mechanism, a plurality of regulating devices for determining the level of the liquid in the 25 containers, said devices being arranged to operate successively on the containers of a group, and means for operating the forwarding devices to present all the containers of each group to the filling mechanism and a part 30 of the containers of each group to some of the regulating devices and the remainder of the containers of each group to all the regulating devices.
- 35 20. A liquid packaging machine including in combination means for forwarding the

containers in spaced groups, a filling mechanism, a plurality of regulating devices for determining the level of the liquid in the containers, said devices being arranged to operate successively on the containers of a group, means for operating the forwarding devices to present all the containers of each group to the filling mechanism and a part of the containers of each group to some of the regulating devices and the remainder of the containers of each group to all the regulating devices, a stoppering mechanism to which the forwarding means presents the containers, and means for simultaneously operating the filling mechanism, the regulating devices and stoppering mechanism.

20. A liquid packaging machine including in combination a feeding mechanism, a filling mechanism, a regulating mechanism for determining the level to which the liquid may rise in the container filled by the filling mechanism, said filling and regulating mechanisms being spaced from each other to allow for a substantial subsidence of the foam as the feeding mechanism advances the container from the filling mechanism to the regulating mechanism.

In testimony whereof, I have hereunto set my hand, in the presence of two subscribing witnesses.

NORBERT M. LA PORTE.
